HENRY M. CHASE, OF HOLYOKE, MASSACHUSETTS, ASSIGNOR TO WORTHINGTON PUMP AND MACHINERY CORPORATION, OF NEW YORK, N. Y., A CORPORATION OF VIRGINIA.

PUMP.

Application filed November 4, 1924. Serial No. 747,722.

This invention relates to improvements in pumps.

The invention aims especially to provide a simple, cheap and durable high pressure pump which may be used with advantage in handling hot liquids, such, for example, as are encountered in the production of gasoline from heavier petroleum products in modern cracking processes. Briefly stated, the present pump comprises novel arrangements for preventing the working parts of the pump, with the exception of the valve service, from contact with hot liquid, with efficient means for protecting the plunger rod stuffing box packing and cooling that part of the plunger rod which on the out-strokes is exposed to the atmosphere, thereby greatly prolonging the continuous operation of the pump and avoiding danger of fire caused by flashing of the hot oil adhering to the plunger rod.

For a full understanding of the invention, a detailed description of preferred and modified constructions embodying the invention will now be given in connection with the accompanying drawings forming a part of this specification, and the features forming the invention then be specifically pointed out in the claims.

30 In the drawings—

Figure 1 is a top plan view of the improved pump in its preferred form;

Figure 2 is a vertical central section thereof, partly in elevation;

35 Figure 3 is a view similar to Fig. 2 of a modified construction, and

Figures 4 and 5 are, respectively, a side elevation, and an end elevation partly in section, of a further modification.

40 Referring now to the drawings, and particularly to Figs. 1 and 2, the pump shown by way of illustration is of the type known as a block pump, the body of which as usual is formed from a single block of metal, such as forged steel, indicated at A. The pump is preferably of the tandem type, in which the plunger bores 21 are formed at each end of the block and preferably in longitudinal alinement. In the bores 21 are mounted liners 22, in which single-acting plungers 23 are mounted and actuated by plunger rods 24 passing through stuffing boxes 25, such rods being connected to cross-heads 26, which latter may be connected to

and reciprocated by any suitable or well-known mechanism. The crossheads 26 are preferably and as shown connected together by tie-rods 27 arranged to slide in guides 28, so that as one of the plungers 23 is making its suction stroke the other plunger 55 will be making a discharge stroke. Extensions 29 in each of the plunger bores 21 are provided which, in effect, form pulsation chambers. These extensions are intersected or cut into by the suction and discharge 60 valve bores, the former being indicated at 1 and the latter at 2. The suction valve bores cut into a suction chamber 3 which is common to both pumps. The discharge 65 valve bore 2 of each pump is intersected by a single discharge passage 4 common to both pumps, such passage in the present case being shown as formed at a right angle to the bores 2, while the passage 4 is preferably formed over a partition 5 which separates the two plunger chambers or extensions 70 29 thereof, although this particular arrangement of the bores and passages is not essential. While, of course, any desired type of valve service suitable for a pump to be used 75 with hot liquids may be provided, preferably and as shown valves of the ball type 8 are employed, with cages 7 held down by spindles 8 extending through and having threaded engagement with plugs 9 screwed 80 into the pump body, lock nuts 10 being provided for holding the spindles 8 in adjusted 85 position.

The stuffing boxes 25 and their packings and the plunger rods 24 are efficiently cooled 90 and protected from direct contact with hot liquid being pumped by providing clearance chambers at the ends of the plunger bores 21 on the dead sides of the plungers 23, such chambers, for the purposes of the 95 present description, being hereinafter referred to as surge chambers, indicated generally at 11. An opening 15 in the plunger bore of the pump at the left hand end of Fig. 2 is connected by a pipe 16 which is 100 tapped into a similar opening 17 on the dead side of the plunger in the bore of the pump at the right hand end of Fig. 2, and on this pipe is mounted a cooler 18 of any suitable or preferred type, into which the 105 cooling medium may be introduced and withdrawn at the openings 19. A small opening 12 communicating with a passage 13 leading

to the suction chamber 3 or other suitable point below the suction valves 13, is provided on one of the pumps, shown as the left hand pump, thus maintaining the body of liquid in the surge chamber under suction pressure. The passages 12, 13, like the valve bores, plunger chambers and suction and discharge passages, as usual in pumps of this type, may be bored in the pump body A, and 10 to facilitate such boring of the passages 12, 13, openings may be formed in the pump body A which may be sealed by screw plugs 14.

From the foregoing it will be noted that 15 as the plungers 23 make their strokes the liquid will be circulated between the surge chambers, and that such liquid will be effectively cooled in its passage through pipe 16, thus protecting the stuffing box packings 20 and cooling the parts of the plunger rods which on the outstrokes of the plungers are exposed to the atmosphere, whereby danger of the hot oil adhering to such rods flashing and causing fire is avoided. It will be noted 25 that whatever loss of oil there may be, make-up will be constantly supplied from the suction by passages 13, 12, to the surge system, and any leakage past the plungers will be returned to the suction.

30 While a tandem pump similar in construction to that shown in Figs. 1 and 2 may have the make-up connection for supplying the surge chambers connected to the discharge side of the pump, as shown in 35 Fig. 3, the connection to the suction side, as above described, is preferable for the reasons hereinafter stated. In the modified construction of Fig. 3, in which corresponding numerals indicate parts similar 40 to those of Fig. 2, the surge chamber 11 on the dead side of the plunger 23 of the pump at the left hand end of Fig. 3 has the opening 15 therein intersected by a bore 30 which intersects discharge passage 4 at its opposite 45 end, so that the make-up liquid is taken from the discharge line instead of the suction side of the pump. The operation of this modified construction is otherwise practically the same as above described with respect to Figs. 50 1 and 2.

It will be understood that the connection to the suction side of the pump, for maintaining the body of liquid in the surge chambers, may be used, also, in pumps other than 55 of the tandem type, and such, for example, as shown in Figs. 4 and 5, which show a pump of the triplex type comprising a battery of three pumps C mounted in any suitable manner in a framework D. The plunger rods 31 are operated through suitable crossheads and crank rods secured to shaft 33, and the cranks are set at 120° with respect to each other, as usual in this type of pump. The shaft 33 is actuated by a gear 60 wheel 35 driven by pinion 36 mounted on

shaft 37 extending through the frame, the latter shaft being driven in any suitable manner, or as shown by a belt-driven pulley 38 of the fast and loose type. In Fig. 5 it will be noted that each of the pumps 70 C is single-acting, and comprises a cylinder 39, suction valve 40, discharge valve 41, and a pulsation chamber connecting these elements. The valve service in this arrangement also includes valves of the ball type, 75 with guards or cages similar to those shown in Figs. 2 and 3. As in the case of the latter figures, also, the plunger bores, pulsation chambers, valve bores and the suction and discharge chamber and passage may be 80 formed in a single compact block of forged steel, so as to efficiently withstand the high pressures for which the pump is intended. In order that the plunger rods 31 and their stuffing boxes may be effectively cooled, 85 each of the cylinder or plunger bores is made of such length as to provide a substantial clearance on the dead sides of the plungers, and these clearance spaces, for the purposes of this description, will be 90 termed surge chambers, indicated generally at 42. Liquid is drawn into these chambers 42 by way of pipes 42', which may be connected to a T-connection to which liquid is supplied by a downwardly extending pipe 95 43 tapped into the pump casing below the suction valves or into the suction line, as preferred. The pipes 42', at their other ends, are connected to annular chambers 44 surrounding the plunger rod stuffing boxes, the 100 latter being mounted in the cylinder heads 45. While a cooler of any well known or preferred type may be employed in either the surge chambers or elsewhere, preferably and as shown a cooler 47 mounted on the 105 pipes 42' is provided. With this arrangement, the plunger rods will work in a comparatively cool liquid medium, which will also protect the stuffing box packing. The cooling of the plunger rods is important, because it prevents danger of fire caused by 110 flashing of the hot oil adhering thereto when exposed to the atmosphere on the outstrokes of the plunger rods.

In all of the constructions above described, 115 it is preferable that the connection for maintaining the liquid supply in the surge chambers shall be to the suction side of the pump. This because such a connection provides for the return to the suction of any leakage past 120 the plungers, and also provides for the maintenance of the suction pressure on the dead sides of the plungers, which, in pumps used in modern cracking processes, is frequently very high, while the head against which the oil is pumped is usually low and there may be but a small pressure differential between suction and discharge. In the present arrangement, this suction pressure is maintained in the body of cool oil on the dead 125 130 135 140 145 150 155 160 165 170 175 180

sides of the plungers, therefore, so that the load carried by the driving parts and the plunger rods, and which depends upon the difference in the pressures on the opposite sides of the plungers, may be quite small.

It will be understood that the invention is not limited to a pump in which the chambers and passages are formed in a single block of metal, and that various changes may be made in the details of construction and arrangement of parts shown and described, while retaining the invention defined by the claims.

What is claimed is:

15 1. A pump for hot liquids, comprising a plunger bore, a single-acting plunger arranged to work in said bore and actuating means for said plunger, a plunger rod stuffing box, a surge chamber in the plunger bore

20 between the stuffing box and the dead side of the plunger, and a connection between the suction side of the pump and the surge chamber.

25 2. A pump for hot liquids, comprising a plunger bore, a single-acting plunger arranged to work in said bore and actuating means for said plunger, a plunger rod stuffing box, a surge chamber in the plunger bore between the stuffing box and the dead side

30 of the plunger, a connection between the suction side of the pump and the surge chamber, and means for cooling the liquid supplied to the chamber.

35 3. A tandem pump for hot liquids, comprising alined plunger bores, single-acting plungers arranged to work in said bores and means for actuating said plungers, surge chambers on the dead sides of the plungers, and a connection between said surge

40 chambers.

4. A tandem pump for hot liquids, comprising alined plunger bores, single-acting plungers arranged to work in said bores and means for actuating said plungers, surge

45 chambers on the dead sides of the plungers, a connection between said surge chambers, and means for cooling the liquid supplied to the surge chambers.

5. A tandem pump for hot liquids, comprising alined plunger bores, single-acting 50 plungers arranged to work in said bores and means for actuating said plungers, surge chambers on the dead sides of the plungers, a connection between said surge chambers, and a connection between the surge system 55 and the pump for supplying liquid to said system.

6. A tandem pump for hot liquids, comprising alined plunger bores, single-acting 60 plungers arranged to work in said bores and means for actuating said plungers, surge chambers on the dead sides of the plungers, a connection between the surge chambers, and a connection between the surge system 65 and the suction side of the pump for supplying liquid to said system.

7. A tandem pump for hot liquids, comprising alined plunger bores, single-acting 70 plungers arranged to work in said bores and move in unison with each other, means for actuating said plungers, surge chambers on the dead sides of the plungers, a connection between said surge chambers, a connection between the surge system and the pump, and means for cooling the liquid in the surge 75 system.

8. A pump for hot liquids, comprising a metal pump body having alined plunger bores therein, single-acting plungers arranged to work in said bores and move in 80 unison with each other, means for actuating said plungers, extensions of said plunger bores forming pulsation chambers between and alined with the plunger bores, suction 85 valve bores intersecting said pulsation chambers, a suction chamber common to both pumps, a discharge chamber common to both pumps, discharge valve bores intersecting said discharge chamber and said pulsation chambers, suction and discharge valves in 90 said bores, surge chambers on the dead sides of the plungers, and a connection between said surge chambers.

In testimony whereof, I have hereunto set my hand.

HENRY M. CHASE.
